UNITED STATES PATENT OFFICE.

FERDINAND J. TILLMAN, OF ST. LOUIS, MISSOURI, ASSIGNOR TO YARD-O-METER CORPORATION, OF ST. LOUIS, MISSOURI, A CORPORATION OF MISSOURI.

DETACHABLE COUNTER BRACKET FOR SUPPORTING FABRIC MEASURING AND COMPUTING MACHINES.

Application filed May 19, 1922. Serial No. 562,158.

This invention relates to an improvement in counter arranged brackets for the support of computing machines and the like used in connection with the measuring of fabrics, and has for its primary object the purpose of providing an improved detachable securing arrangement for demountably securing a bracket at different places on a counter.

Another object of the invention is in providing improved vertical adjusting means in connection with the bracket.

A further object of the invention is in providing a removable counter bracket with improved automatic securing means and with detachable means that are made co-operable with the automatic securing means.

Other and further objects will appear in the specification and be specifically pointed out in the appended claims, reference being had to the accompanying drawings, exemplifying the invention, and in which:

Figure 1 is a side elevation of a counter having its intermediate portion broken away and showing a series of elements secured to the edge of the counter with which this improved bracket is co-operable, and showing the improved bracket in co-operation with one of the elements.

Figure 2 is an enlarged fragmentary vertical section taken approximately on the line II-II of Fig. 3.

Figure 3 is an enlarged vertical section taken approximately on the line III-III of Fig. 2.

Figure 4 is an enlarged horizontal section taken approximately on the line IV-IV of Fig. 2.

Figure 5 is an enlarged section taken approximately on the line V-V of Fig. 3.

Figure 6 is an enlarged horizontal section taken on the line VI-VI of Fig. 2.

Referring by numerals to the accompanying drawings 1 designates a counter having a top 2 and secured to an edge of said top are a series of stationarily held base members 3, each of said members 3 being provided with a pressed out portion 4 which is formed intermediate of its ends and arranged parallel to the edge of the counter top, said portion 4 being provided with a receiv-

ing opening 5 from which an angular disposed slot 6 is extended, the upper edge of said slot forming a cam surface 7, the lower edge of said slot being provided with a series of ratchet teeth 8.

The supporting bracket 9 which is co-operable with each of the base members 3 is comprised of a vertically extending portion 10 in which is formed a vertically extending cylinder 11 which is closed at its lower end as designated at 12, and formed integral with said extending portion 10 is a base portion 13 having an integrally formed depending portion 14, said portion 14 being depended below the top surface of the counter 2, thereby providing a housing 15.

Formed within said housing are a pair of inverted seating portions 16 and secured against each of said seating portions by a respective screw 17 is an angularly disposed portion 18 of a trigger carrying plate 19, and horizontally extended from said plate is a pin 20 bearing a trigger 21.

The trigger 21 is provided with a pawl 22, said pawl extending through an opening 23 which is formed in the plate 19, said trigger being borne on the outside of said plate, as shown in Figs. 2 and 4 and is provided with a depending finger engaging portion 24, there being a coil spring 25 for normally holding the pawl 22 in engagement with the ratchet teeth 8 which are formed on the edge of the slot 6 of each respective base member 3, thus preventing the pin 20 from being disengaged from the slot 6.

As already mentioned in one of the objects of this invention, this improved detachable bracket is for the support of a computing and measuring machine, and as designated in the drawings as 26, said machine having a base 27 from which is depended a shoulder 28, and extending downwardly from said shoulder is a projection 29 which is secured by a pin 30 to the upper end of a plunger 31 having a closed lower end 32.

The tubular member 31 is adapted to be vertically held within the cylinder 11 of the bracket 9, and secured to the closed end 32 of said tubular member 31 by the bolt 33 is a packing element in the form of an inverted

leather cup 34 which is adapted to peripherally engage the wall of the cylinder 11, thereby providing a compression compartment 35 beneath said cup 34.

5 The tubular member 31 is provided with a vertically extending slot 36, and extended through said slot and through the wall of the cylinder 11 is the threaded end 37 of a clamping member 38, said member 38 being 10 provided with a handle 39.

The threaded end 37 of the member 38 is engaged within a clamping block 40, said block being located within the tubular member 31, so that when the member 38 is 15 manipulated towards tightening a portion of the wall of the tubular member 31 will be clamped between said block 40 and a portion of the wall of the cylinder 11, as shown more clearly in Fig. 2.

20 It is to be noted that each of the base members 3 is provided with an edge 41 which is arranged on a plane above the top surface of the counter top 2, said raised edge being for the purpose of receiving the under 25 side of each of the angularly disposed portions 18 of the trigger carrying plate 19, when the bracket 9 is being mounted into position upon the counter, and for preventing the lower end 42 of the vertically extending portion 10 of the bracket 9 from engaging the surface top of the counter, a 30 roller 43 is secured beneath the base portion 14 of said bracket.

In the mounting of a device of this improved character to a counter for the purpose of supporting the computing machine 26 thereabove, the pin 44 bearing the shoulder 45 which is horizontally extended from the trigger carrying plate 19 inwardly 40 thereof, is engaged into the receiving opening 5 of the slot 6, and in which the bracket 9 is borne to the left and permitted to rest upon the counter top 2, the roller 43 directly engaging said counter top while the portions 18 of the trigger plate 19 will slidingly 45 rest upon the upwardly extending edge 41 of the base member 3 to which the bracket 9 is being secured.

The leftward sliding movement of the 50 bracket 9 to the base member 3 upon the introduction of the pin 44 within the slot 6 as just related, will cause said pin to bear against the cam surface 7 of said slot 6, and since said cam surface is inclined downwardly the bracket 9 will be drawn tightly 55 against the top of the counter, and while said leftward movement of the bracket is taking place the pawl 22 of the trigger 21 will automatically engage the ratchet teeth 8 of the 60 slot 6 thereby preventing retrograde movement of the bracket 9, and in which said bracket will be locked in a secure position to the base member 3 of the counter.

If it is desired by the operator to 65 vertically adjust the machine 26, the handle 39

of the clamping member 38 is engaged and turned towards loosening and the machine is then either elevated or lowered, and when a desired vertical height has been attained the clamping member 38 is then tightened, 70 in which the clamping block 40 will be drawn against a portion of the wall of the tubular member 31 thereby clamping said wall portion against a portion of the wall of the cylinder 11. 75

In the event that the machine 26 is to be lowered, after the clamping member 38 has been manipulated towards loosening, the machine 26 can not be lowered with rapidity 80 on account of air being confined within the compartment 35 which is formed at the lower end of the cylinder 11, and in which the air will be permitted to escape slowly through the small vent opening 46 which is provided in the closed end 12 of said cylinder, the confined or trapped air within said compartment 35 serving as a cushion to the descending tubular member 31 of the machine 26. The purpose of providing the cushioning means as just described is so that 85 accidents will be prevented to portions of the hands or fingers of the operators in the event that the hands are allowed to be positioned between the shoulder 28 of the machine 26 and the top of the extending portion 10 of the bracket 9. 90

A demountable bracket of this improved character is essential in connection with computing and measuring machines as it is quite often desired to shift such supporting brackets to different locations on a counter, and when it is desired to detach or dismount this improved bracket from a base member 3 to which it is secured, the finger engaging portion 24 of the trigger 21 upon being 100 pressed upwardly, will release the pawl portion of said trigger from engagement with the ratchet teeth 8 of the member 3, thereby permitting the bracket 9 to be moved to the right so that the pin can be disengaged from 105 the slot 6. 110

What I claim is:—

1. The combination of a counter and a detachable bracket therefor, a base member borne by said counter having a horizontally 115 inclined cam surface, said bracket having a projection for horizontal co-operation with said cam surface of said member horizontally disposed teeth provided on said member, and a locking element borne by said bracket 120 for co-operation with said teeth of said member.

2. The combination of a base member and a detachable bracket therefor, said member adapted to be secured to an edge of a counter 125 and provided with a horizontally inclined slot, a series of teeth formed on one edge of said slot, said bracket having a horizontally extending pin which is adapted to be slidingly engaged in said slot of said member, 130

and means carried by said bracket co-operable with the teeth of said member for preventing said pin of said bracket from being disengaged from the slot of said member.

5 3. The combination of a counter and a detachable bracket therefor, horizontally inclined cam means borne by said counter and

related to said bracket, said cam means having a series of horizontally disposed teeth, a projection co-operable with said cam means and said bracket, and means carried by said bracket for engaging with the teeth of said cam means.

FERDINAND J. TILLMAN.
